Des. 234,544
Patented Mar. 18, 1975

234,544

X-RAY APPARATUS

Vitislav Yakovlevich Bobov, Bolsheokhtinsky prospekt 12, kv. 42; Ernest Mikhailovich Belopolsky, Naberezhnaya Lazareva 20, kv. 32; Genrikh Leivovich Troyansky, prospekt Energetikov, 54 korpus 1, kv. 160, and Avrum Lvovich Farberg, ulitsa B. Ozernaya 86, kv. 1, all of Leningrad, U.S.S.R.

Filed Mar. 26, 1973, Ser. No. 345,196

Term of patent 7 years

Int. Cl. D24—01
U.S. Cl. D83—1 H

FIG. 1 is a perspective view of an X-ray apparatus showing our new design;

FIG. 2 is a front view of the apparatus of FIG. 1;
FIG. 3 is a rear view of the apparatus of FIG. 1;
FIG. 4 is a top plan view of the apparatus of FIG. 1;
FIG. 5 is a bottom plan view of the apparatus of FIG. 1; and

FIG. 6 is a side elevational view of the apparatus of FIG. 1.

We claim:

The ornamental design of an X-ray apparatus, as shown.
